UNITED STATES PATENT OFFICE

169,309

TOY BANK OR SIMILAR ARTICLE

Ving Fuller, Sherman Oaks, Calif.

Application October 6, 1952, Serial No. 21,734

Term of patent 14 years

(Cl. D34—11)

To all whom it may concern:

Be it known that I, Ving Fuller, a citizen of the United States, residing at 4546 Stern Ave., Sherman Oaks, in the county of Los Angeles and State of California, have invented a new, original, and ornamental Design for a Toy Bank or Similar Article, of which the following is a specification, reference being had to the accompanying drawing, forming a part thereof:

Fig. 1 is a perspective view of a toy bank or similar article, showing my new design;

Fig. 2 is a top plan view thereof;

Fig. 3 is a side elevational view thereof;

Fig. 4 is a bottom plan view thereof;

Fig. 5 is a front elevational view thereof; and

Fig. 6 is a rear elevational view thereof.

I claim:

The ornamental design for a toy bank or similar article, as shown.

VING FULLER.
